UNITED STATES PATENT OFFICE.

CHARLES L. BESSONETTE, OF WACO, TEXAS.

BALING-PRESS.

SPECIFICATION forming part of Letters Patent No. 603,249, dated May 3, 1898.

Application filed March 9, 1896. Serial No. 582,422. (No model.)

To all whom it may concern:

Be it known that I, CHARLES L. BESSONETTE, a citizen of the United States, residing at Waco, in the county of McLennan and State of Texas, have invented certain new and useful Improvements in Machines for Baling Cotton; and I do hereby declare the following to be a full, clear, and exact description of the invention, such as will enable others skilled in the art to which it appertains to make and use the same.

My invention consists in the novel features hereinafter described, reference being had to the accompanying drawings, which illustrate one form in which I have contemplated embodying my invention, and said invention is fully disclosed in the following description and claims.

Referring to the said drawings, Figure 1 represents a front elevation of a machine embodying my invention. Fig. 2 represents a side view of the same. Fig. 3 represents a vertical transverse sectional view of the same, showing also the air-pump and its connections. Fig. 4 is a diagrammatic view showing the action of the compressing-rollers in forming the bale.

In the drawings, A represents the bed-plate of my improved machine, supported upon a suitable foundation and upon which the main frame B of the machine, carrying the working parts, rests. The main frame consists in this instance of two side plates or frames connected by the bed-plate at the bottom and by suitable cross-braces between the bed-plate and the upper extremities.

C and D represent the upper compressing-rollers of the press, which are mounted in stationary bearings in the main frame of the machine and are disposed preferably with their axes in a horizontal plane. One of these rollers—in this instance roller C—is provided at each end with an annular flange c^x , extending outward a considerable distance beyond the periphery of the roller to prevent the telescoping of the cotton laps in forming the bale. Above the rollers C and D is a feeding and compressing roller E, which is also mounted in stationary bearings in the main frame and has its periphery but a very

slight distance from the roller C, so that the bat of cotton will be fed into the machine by and compressed between the rollers C and E. Adjacent to the rollers C and D and slightly above the same is a guide-board E', over which the bat passes and by which it is guided to the rollers C and E.

Below the rollers C and D is a vertically-moving compressing-frame F, which is arranged to slide vertically in the main frame of the machine. This frame carries the lower compressing-rollers G and H, preferably of the same size as the rollers C and D and also having their axes in a horizontal plane, the shafts of said rollers being mounted in bearings carried by the said sliding compressing-frame. It will be seen by reference particularly to Fig. 2 that the rollers are so arranged that they exert pressure upon the bale in pairs diametrically opposite to each other, and the roller of the lower pair which is diametrically opposite to the flanged roller C of the upper pair—to wit, the roller H—is also provided at each end with flanges h^x similar to those of the roller C, as illustrated in the drawings. These flanges confine the ends of the bale when it is being first formed and give it smooth ends, perpendicular to its axis of rotation. The central part of the bed-plate A is provided with a central aperture K, into which a hydraulic cylinder L is dropped, said cylinder having a flange l at its upper end, which engages the bed-plate adjacent to the edges of said central aperture. A large hollow piston M or plunger of substantially the diameter of the interior of the cylinder L engages said cylinder, the cylinder being provided with the usual packing and packing-flange l' . The upper end of said hollow flange or piston is closed in this instance by a part of the vertically-sliding compressing-frame F, as shown, so that the hollow plunger or piston is made air-tight. At its lower end said hollow piston or plunger is provided with an aperture m , communicating with the interior of the cylinder L, said aperture being provided with a regulating-valve m' , which has a valve-stem m^2 , preferably having a threaded portion extending through the upper end of piston to a point where it can be 100

reached by the operator, where it is provided with a hand-wheel m^3 and a jam-nut m^4 . By this means the aperture may be adjusted as desired.

5 The cylinder I is partly filled with a fluid, such as water or oil, which when the piston is down passes into the hollow piston M through the aperture m , a suitable means being provided for the escape of air from the 10 said piston, as indicated in Fig. 3.

O represents an air-pump of any suitable form provided with an adjustable pop or safety valve o of any usual or preferred form, which may be set to discharge at any given 15 pressure.

o' represents a service-pipe leading from the air-pump to the machine and connected by a flexible pipe o^2 with a nipple m^5 , communicating with the piston. I also prefer to 20 provide a pressure-gage P, which is conveniently secured to the main frame, as shown, and connected with the service-pipe by a small pipe p . I also provide an exhaust-cock O' in the service-pipe, so that the air may be 25 allowed to escape from the interior of the piston when it is desired to lower the piston to discharge a bale or for any other reason.

Q represents the main or driving shaft of the machine, mounted in bearings in the main 30 frame and provided with a driving band-pulley q and with pinions $q' q'$, which engage large gear-wheels $e e$ on the shaft of the roller E. This roller-shaft is also provided with pinions $e' e'$, which engage pinions $c c$ and $d d$ 35 on the shafts of rollers C and D and drive said rollers. In order to impart motion at all times and in all positions to the lower compressing-rollers, I provide a movable idle-shaft R, which is connected pivotally with 40 the shaft of roller E by arms $R' R'$ and by similar arms $R^2 R^2$ with a shaft F', journaled in the vertically-movable compressor-frame F. The shaft F' is provided at each end with a gear-wheel f , similar to gear-wheels $e e$, and 45 the movable shaft R is provided with similar gear-wheels $r r$, which transmit power from the wheels $e e$ to wheels $f f$. The shaft F' is also provided with pinions $f' f'$, which mesh with pinions $g g$ and $h h$. By this means all 50 of the rollers will be driven at the same speed and in the proper direction, as will be seen by reference to the arrows in Fig. 3.

In carrying out my invention I employ compressing-rollers which are preferably of 55 a size considerably smaller than the size of the bale to be formed, whereby but a very small part of the surface of each roll is in contact with the bale at once and the peripheries of the rolls curve away sharply from the 60 bale. As a result of this construction as the bat is rolled onto the bale the rollers each push the cotton forward, as is clearly indicated in Fig. 4, thereby exerting a longitudinal strain upon the bat as each layer is rolled 65 on and drawing the fibers longitudinally. As a result of this drawing action the cotton is laid more smoothly and tightly upon the roll

and a much better bale is produced than in a machine using large rollers.

It will also be noted that by my invention 70 the pressure is applied to the bale at four points and the pressure of each roller is met by that of another diametrically opposed to it. By acting on the bale in this manner the same amount of compression can be obtained 75 with a very greatly reduced pressure upon the rolls, and this enables me to make the machine lighter and save a great amount in building and also in the power required to operate the machine. 80

The operation of the machine is as follows: The air-pump is started and air is forced into the hollow piston, forcing it to move upwardly. At the same time the air-pressure being downward upon the fluid as well as upward the 85 fluid is slowly forced through the aperture as the piston rises into the lower parts of the cylinder. The piston, being of the size of the cylinder throughout its length, forms a guide for the sliding compressing-frame and prevents any tendency of the same to get out of a horizontal plane when the lower rollers have reached their highest point, and even before the machine can be started and the cotton-bat fed in between rollers C and E, 90 where it is somewhat compressed, after which it passes into the space between the four compressing-rollers, where it is rapidly formed into a roll. As this roll becomes larger it will gradually begin to exert a pressure upon the 100 rollers D C G II, and the pop or safety valve having been set to a certain pressure as soon as the pressure between the upper and lower rolls exceeds that to which said valve is set it will automatically open and let off a small 105 quantity of air, thus lowering the piston and the rolls G H. In this manner the rolls G II are gradually lowered as the bale increases in size, at the same time maintaining the desired pressure upon the bale, which pressure 110 can be regulated by adjusting the valve in the manner usual with such valves. When the bale has assumed the proper size, the binding-wrapper T is put on in the usual or any preferred manner, as shown in Fig. 1, 115 the exhaust-cock Q' is opened, and the air allowed to escape from the piston. The liquid in the cylinder will be forced up into the piston during the baling operation, and when said cock is opened the weight of the piston, 120 sliding frame, rolls, and bale will further tend to force it up into the piston. The aperture m , being regulated by the valve m' , will be so small that the liquid will be forced to pass slowly through the said aperture m , and thus 125 slowly lower the piston, rollers G H, and the bale. The bale will then be removed and the operation repeated.

It will be seen that by employing a body of liquid and a fluid, such as air, (or other gas,) 130 above the same, which is more compressible, I obtain a number of advantageous results. The body of air will exert a constant pressure upon the piston, and slight variations in

its elevation will not interfere with the exertion of this pressure on account of the greater degree of compressibility of the air in contrast to a liquid. The liquid serves as a seal and also as a base against which the more compressible fluid can react, and by the construction which I employ there cannot be any moment when all pressure is taken off of the bale, as sometimes happens where a liquid only is employed.

What I claim, and desire to secure by Letters Patent, is—

- 15 1. In a cotton-baling press the combination with the stationary compressing-rollers, of movable compressing-rollers, each disposed diametrically opposite with respect to the bale to one of said fixed rollers, of a hydraulic cylinder, a hollow piston in said cylinder operatively connected with said movable rollers
- 20 2. having a communication between said cylinder and the interior of said piston, means for forcing air into said piston, and automatic devices for exhausting the air from the interior of said piston, substantially as described.
- 25 2. In a cotton-baling press, the combination

with the movable and stationary compressing-rollers, of a hydraulic cylinder, a hollow piston in said cylinder for moving the movable compressing-rolls, having a communication between the interior of said piston and said cylinder, means for forcing a fluid into said piston and an automatic device for exhausting fluid from said piston, substantially as described.

3. In a cotton-baling press, the combination with the movable and stationary compressing-rollers, of a hydraulic cylinder, a hollow piston engaging said cylinder and having an aperture forming a communication between the interior of said piston and cylinder, a regulating-valve for said aperture, means for forcing a fluid in said piston and an automatic relief-valve for said piston, substantially as described.

In testimony whereof I affix my signature in presence of two witnesses.

CHARLES L. BESSONETTE.
